UNITED STATES PATENT OFFICE.

PHINEAS H. YORK, OF CHICAGO, ILLINOIS, ASSIGNOR TO THE TONK MANUFACTURING COMPANY, OF SAME PLACE.

DESIGN FOR A PEDESTAL FOR PIANO-STOOLS.

SPECIFICATION forming part of Design No. 34,089, dated February 12, 1901.

Application filed January 8, 1900. Serial No. 783. Term of patent 3 $\frac{1}{2}$ years.

To all whom it may concern:

Be it known that I, PHINEAS H. YORK, a citizen of the United States, residing at Chicago, in the county of Cook and State of Illinois, have invented and produced a new and original Design for Pedestals for Piano-Stools, of which the following is a specification, reference being had to the accompanying drawings, in which—

10 Figure 1 is a perspective view of a piano-stool pedestal embodying my design, and Fig. 2 is a side elevation of the same.

The characteristic features of my design comprise a centrally-elevated cruciform base, 15 as A, the several arms *a* of which form the legs of the pedestal. From each arm or leg member *a* and also from the center of the base rise standards or pillars, as *b'*, which are of ornamental form, being made angular in 20 cross-section and made tapering downwardly throughout their main central portions. Each

of the said pillars, except the center one, is provided near each end with turned spherical ornaments, as indicated at *b² b³*. The several pillars are surmounted by a cap-piece 25 *C*, which approaches a cruciform shape, the side margins thereof being scalloped or provided with curved indentations *c* between each of the pillars, so as to approximately outline the four arms of a cross, the outer end 30 of each of which is supported by one of the outer pillars. The base is also provided beneath the elevated central portion thereof with a pendant or ornamental drop *a'*.

I claim—

35 The design for a piano-stool pedestal, substantially as herein shown and described.

PHINEAS H. YORK.

Witnesses:

FREDERICK C. GOODWIN,
ALBERT H. GRAVES.
